[57] CLAIM

The ornamental design for surgical headlight, as shown and described.

DESCRIPTION

FIG. 1 is a perspective view of a surgical headlight showing my new design, the broken lines being shown for illustrative purposes only;

FIG. 2 is a front elevational view of the surgical headlight on an enlarged scale, the light being pivoted to an alternate position;

FIG. 3 is a top plan view thereof;

FIG. 4 is a right side elevational view thereof;

FIG. 5 is a rear elevational view thereof;

FIG. 6 is a bottom plan view thereof; and,

FIG. 7 is a left side elevational view thereof.
